UNITED STATES PATENT OFFICE.

LOUIS C. KRUMMEL, OF CLINTON, CONNECTICUT.

AUTOMATIC SIGNAL AND STOP FOR RAILWAYS.

1,117,862.

Specification of Letters Patent.

Patented Nov. 17, 1914.

Application filed March 12, 1913. Serial No. 758,722.

To all whom it may concern:

Be it known that I, LOUIS C. KRUMMEL, a citizen of the United States, and a resident of Clinton, in the county of Middlesex and State of Connecticut, have invented a new and Improved Automatic Signal and Stop for Railways, of which the following is a full, clear, and exact description.

This invention relates to improvements in signals and stop devices for railways, and has for an object to provide an improved structure which will signal the engineer under certain circumstances, and will automatically stop the train unless positively held in an inoperative position by the engineer.

A further object of the invention is to provide a signaling and stop device for railway trains which will properly operate for shutting off the power and then applying the brakes if allowed to operate, but which will not affect the power supply of the brakes if held out of operation by the engineer, whereby the engineer will have absolute control over the engine at all times, but when negligent or incapacitated for any reason, the mechanism will automatically operate.

A still further object of the invention is to provide a signaling device which is adapted to be operated with equal facility either from trip or contact rails on the ground or overhead, and which will operate either with stationary rails or with adjustable removable rails, in either position, namely, on the ground or overhead, so that the device may operate at any time and in any place.

A still further object of the invention is to provide a signal and train stopping device which is operated mechanically and positively when the various stops or rails are set for the operation thereof.

In carrying out the objects of the invention, auxiliary rails are provided adjacent the usual rails of the track, or if desired, are placed overhead. Under some circumstances overhead and ground rails are provided so that they may operate under all conditions. Arranged on the cab of the locomotive is a mechanism associated with the air brake system and with the throttle valve, or if desired, with the steam-controlled valve, for actuating these valves according to the condition of the track ahead. This mechanism is associated with a vertically movable rod which extends downwardly to a position below the engine and

carries a shoe which is pivotally fixed to a suitable bracket on the engine so as to come in contact with the stop or signal rails arranged adjacent the track. When the shoe is in contact with the signal rails the vertically movable rod is moved for a certain distance and when the shoe comes in contact with the stop rail, the vertically movable rod is moved an additional distance for causing the throttle to be shut off unless positively held open by the engineer. When the signal rail is engaged by the shoe a bell or other signal is sounded which may be operated mechanically, or may be operated electrically, as desired. These contact rails may be arranged either on the ground or above the engine. When arranged above the engine the vertically movable rod is provided with a suitable extension which is connected with the upper shoe designed to contact with the upper signal and stop rails. Both the upper and lower signal and stop rails are adapted to be arranged either fixed or adjustable. The adjustable stop rail is very desirable under some circumstances, as the same may be set at any time for causing a train passing over the track to be stopped at that point in case of danger ahead or for any other desired reason.

A practical embodiment of the invention is represented in the accompanying drawings forming a part of this specification, in which similar characters of reference indicate corresponding parts in all the views.

Figure 1 is a transverse section through the cab of an engine disclosing the rear view of an embodiment of the invention; Fig. 2 is an enlarged side view of the shoe disclosed in Fig. 1; Fig. 3 is a side view of an adjustable signal rail and stop rail; Fig. 4 is an enlarged horizontal sectional view through the operating mechanism disclosed in Fig. 1, the same being shown with the throttle valve open and the air brake system closed; Fig. 5 is a view similar to Fig. 4 except that the parts have been released; Fig. 6 is a side view of the invention applied, the same disclosing a slightly modified form of the invention to that disclosed in Fig. 1; Fig. 7 is a rear view of the bottom part of the device shown in Fig. 6; Fig. 8 is another slightly modified form of signaling device. Fig. 9 is a view similar to Fig. 1 except that the same discloses a slightly modified form of the invention in which either a ground rail or an overhead rail may be used; and

Fig. 10 is an enlarged detail fragmentary sectional view approximately on the line 10—10 of Fig. 9.

Referring to the accompanying drawings by numerals, 1 indicates the usual rails of a track, on which the wheels of the engine and cars rest. Arranged parallel with the rails 1, either at one side thereof or between the rails, is an extra or third rail 2 arranged in line with, but in front of a second or extra third rail 3 (Fig. 2). It will be observed that the third rail 2 is lower than the third rail 3 so that the shoe 4 may be partially actuated when it strikes rail 2 and completely actuated or moved when it strikes rail 3. These two movements are intended to cause different operations in the cab, as hereinafter fully described, the first movement causing a signal to be sounded and the second movement causing the air brake system to be applied. The rail 2 is known as the signal rail, while rail 3 is known as a stop rail, as the same will cause the train to stop unless the engineer takes steps to prevent said stoppage. If desired, the rails 2 and 3 could be arranged as shown in Fig. 3, wherein the rail 2 is pivoted at 5, while rail 3 is pivoted at 6. Links 7 and 8 are pivotally connected with the rails 2 and 3, respectively, and with bell crank levers 9 and 10. The levers 9 and 10 are connected by a rod 11, while lever 10 has associated therewith a rod 12 designed to be operated by any desired means, as for instance a semaphore, so as to raise and lower rails 2 and 3. When it is desired to stop the train or cause a signal to be sounded therein, rod 12 is operated by raising rails 2 and 3, whereupon shoe 4 will engage the same and cause the signals to operate and stop the train as hereinafter fully described.

The shoe 4 is preferably formed with a wearing member 15 connected in any desired manner with the body 16, the body 16 being formed with an extension 17 which is continually pressed by a spring 18 held in one position by any desired means associated with bracket 19. The opposite end of the body 16 to extension 17, carries a pivotal shaft 20 which is rigidly secured to body 16 so as to turn therewith. A crank arm 21 is rigidly secured to shaft 20 so as to move upwardly and downwardly a vertically movable rod 22 pivotally connected therewith. Arranged adjacent shoe 4 is a snow plow or scraper 23 designed to protect the moving parts of the shoe against being clogged with snow or ice.

The bracket 19 carries a tube 24 which acts as a guide for rod 22. The tube 24 extends upwardly through the bottom of the cab 25 to a casing 26 where the same is rigidly secured by any desired means, as for instance being threaded thereto, as clearly shown in Fig. 4. Referring more particu-

larly to Figs. 4 and 5, it will be seen that the rod 22 is provided with an enlarged opening 26' and a reduced guiding member 27 and a head 28. The opening 26' accommodates a pin 29 rigidly secured to the hook 30 pivotally mounted on shaft 31. The hook 30 is provided with a rack 32 at the end opposite the hook portion so as to mesh with a pinion 33 which is mounted upon a suitable shaft 34 and which rotates a sign 35, whereby when the hook 30 is in its disengaged condition, as shown in Fig. 5, the sign 35 will be brought to view, but when the hook is in its engaged or outward position, as shown in Fig. 4, the sign will be hidden. The size of the opening 26' is sufficient for permitting the proper pivotal movement of hook 30 and also for permitting a lost motion effect in regard to rod 22 so that head 28 may be lowered for causing the point 36 thereof to engage the contact 37 without causing the hook 30 to be disengaged from the hook end 38 of bar 39. When point 36 engages contact 37, an electrical circuit is established through lamp 40, bell 41, battery 42, and connecting lines. It will be evident that there is an independent circuit for the bell and for the lamp, though preferably a common return is provided. When the shoe 4 engages rail 2, as shown in Fig. 2, rod 22 will be moved downwardly for a predetermined distance or until point 36 and head 28 (Fig. 4) are in engagement with contact 37. This will cause the signals 40 and 41 to be operated and the same will continue to operate as long as shoe 4 is in contact with rail 2. When the shoe 4 moves off rail 2 on to rail 3, rod 22 will be moved an additional distance so as to move the hook 30 to a disengaged or open position, as shown in Fig. 5. When hook 30 is disengaged, as shown in Fig. 5, spring 43 acting on the partition 44 will press the sliding member or block 45 and cause the same to move outwardly or longitudinally of the casing 26. This will pull the rod 39 and cause the lug 46 to strike against and move lug 47 so as to operate a counting mechanism 48 and thereby indicate that the stop mechanism has been operated. Rod 39 is provided with a stop 49 designed to be engaged by end 50 of lever 51. Lever 51 is pivoted to the casing 26 so that whenever the lever 51 is moved in one direction, the hook end 38 will be moved over to the position ready to engage hook 30. The movement of hook end 38 of bar 39 in this manner will contract spring 43 and again draw the sliding block 45 into casing 26 and thereby release the throttle 52. The throttle lever 52 is rigidly connected with the shaft 53, which in turn is connected to any kind of a throttle valve desired, so that when lever 51 is moved to the position shown in Fig. 4, the throttle valve is opened and steam is supplied to the

engine cylinders, and when the throttle lever 52 is in the position shown in Fig. 5, the steam will be shut off from the engine cylinders.

5 The position shown in Fig. 4 of lever 52 is known as the neutral position, and if the lever 52 is moved pivotally toward the arm 54, power will be transmitted through the pivotally mounted link 55 to lever 54 for 10 shifting the position thereof, as shown in Fig. 1, in order to open the pipes of air brake system and apply the air brakes. By 15 reason of the slot 56 in link 55, the throttle may be closed without opening the air brake system. This will allow the train to coast and will also allow the air brake system to be operated to any desired extent for slowing down. However, if the engineer releases both the levers 51 and 52, the spring 20 43 will move block 45 to such an extent as to cause lever 54 to take the position shown in Fig. 1 and thus turn off the steam and apply the brakes. In order to cause a free movement of lever 52 in one direction or in both 25 directions when hooks 38 and 30 are in engagement, block 45 is provided with a bore in which is slidingly fitted a bar 57. The bar 57 is adapted to press against shoulder 58' at one end and at the opposite end to 30 be pivotally connected with lever 52, whereby when spring 43 is acting on block 45, movement will be transmitted to lever 52 for moving the same to the position shown in Fig. 1, but when block 45 is held against 35 movement, lever 52 will be free to move in either direction, according to the desires of the engineer. Near the upper end of lever 52 is arranged a lug 58 designed to be engaged by a hook 59 which is pivotally connected at 40 60 to an extension from block 45. A spring 61 normally presses against hook 59 for holding the upper part of the same slightly away from block 45 and for causing a proper engagement between the lug 58 and hook 59. This arrangement provides 45 means for locking lever 52 against being moved to an open position unless lever 51 is previously actuated and continually held in operative position by the engineer. If 50 desired, the throttle valve connected with shaft 53 could be so arranged as to be at a half open position when the lever 52 is in the position shown in Fig. 5, whereupon the hook 59 will cause the train to move at half 55 speed when the various devices are in the position shown in Fig. 5. It will necessitate the engineer holding lever 52 in order to proceed at half speed as spring 43 would cause a complete closing of the throttle valve 60 and an opening of the air brake system, as shown in Fig. 1, unless the lever was held against movement. It will, of course, be noted that if desired lever 51 could be operated for withdrawing block 45 and hook 59 so that lever 52 could be moved to the

position shown in Fig. 1, and thus allow the train to proceed at full speed or allow the train to have a full head of pressure when starting. This is very desirable in heavy freight engines where the initial energy required is considerable. Also it will be noted that by the arrangements set forth, the engineer has absolute control over the action of the engine and may proceed at any speed but unless he takes actual steps to control his engine the same will automatically stop.

In connection with the actuation of the mechanism shown in Figs. 4, and 5, it will be noted that the same may be actuated from the ground as shown in Fig. 1, or from an overhead wire, as shown in Figs. 9 and 10. On certain parts of the track it may be desirable to have one form of rail, and on another part of the track it may be desirable to have another form of rail, so that the structure will properly act on any part of the track, and which may be supplied with either overhead or ground rails.

Referring more in detail to Figs. 9 and 10, 62 is a reciprocating housing formed with a contact extension 36' which acts in a similar manner to the extension 36 shown in Figs. 4 and 5. The head 28 of rod 22 is deprived of the extension 36 in the structure shown in Fig. 9 so as to properly reciprocate in housing 62. A spring 63 is provided for returning housing 62 to its original elevated position when moved therefrom, and then released. Pivotally connected with housing 62 is a lever 64, which in turn is rigidly secured to shaft 65 mounted on the top of the cab by any desired means, as for instance by suitable brackets 66. Shaft 65 carries shoes 67 designed to engage an elevated signal rail 68 which is pivotally mounted at 69 on a suitable support 70. An arm 71 is rigidly connected with rail 68, which arm is actuated by suitable bell crank levers and rods 72 by any desired means, as for instance a semaphore or a hand-operated lever. In connection with the hook or extension 36', it will be evident that the same may engage the contact 37 as shown in Fig. 4, for operating the mechanism shown in Fig. 4, or may be caused to engage a suitable contact lever 73 to which is secured a hammer 74. When the extension 36' engages the contact 73 and moves past the same, hammer 74 will be moved so as to strike bell 75 unless a suitable spring acting on extension 73 is provided for causing a return movement thereof. This indicates a mechanical way of sounding the signal, but other mechanical means could be provided without departing from the spirit of the invention, or the structure shown in Fig. 4 could be used wherein an electrical bell is sounded and an electrical light is supplied with current.

The movement of rod 22 either in the structure shown in Fig. 4, or that shown in Fig. 9, is first arranged to cause a signal to be sounded and afterward to cause a release of hook 38 and consequently a releasing of spring 43 in order that the same may shut off the steam and turn on the air brakes. In order to cause this action, pin 29 is allowed to operate in the enlarged aperture 26', whereby a signal will first be sounded and then mechanism operated, in case the signal rail 2 is followed by a stop rail 3. In the showing disclosed in Fig. 9, only a signal rail is disclosed, but it will be evident that the same could be followed by a stop rail for causing a further downward movement of rod 22. If desired, in the showing disclosed in Fig. 2, the opening 26' need not be provided except for the proper 20 pivotal movement of hook 30 as the sliding of housing 62 is independent of the action of rods 22 within certain limits.

In Fig. 8 will be seen a slightly modified form of the invention, in which a slightly changed form of signal is shown. In this form of the invention, a signal lamp 76 is provided and also a bell 77. These signal devices are connected to a source of current supply 79 by suitable wiring 80 and also to shoe 81 and a bond 82, together with rails 1 and 2, and the wheels of the locomotive. The hook part of shoe 81 is insulated from the upper part so that when shoe 81 contacts with rail 2, current will flow from battery 79 through wire 80, bottom part of shoe 81, rail 2, bond 82, rail 1, and the wheels and axles of the engine, and also through the lamp 76 and bell 77. Aside from the insulation of shoe 81, the remaining part of the shoe is the same as that shown in Fig. 2, and therefore will need no additional description. This shoe will operate the mechanism shown in Figs. 4 and 5 as heretofore described.

In Figs. 6 and 7 will be seen another slightly modified form of the invention, in which the signal rails and the stop rails are not arranged in alinement, whereby the signal rails may be caused to operate at any time without affecting the stop rails. Referring in detail to these figures, 83 indicates the stop rail designed to be engaged by a shoe 4 which will actuate the mechanism in the cab as described in respect to Figs. 1, 4 and 5. The bell 84 and the lamp 85 are operated in a slightly different way from that shown in Figs. 4 and 8. In order to properly actuate these signals, the signal rail 86 arranged alongside 60 of the rail 1 is provided so as to readily engage the shoe 87 pressed by a suitable spring 88 in order to provide a proper contact. If desired, the shoe 87 may be insulated from the engine by a suitable strip of insulation 65 89 or by any other form of insulation. A

connector 90 is used for connecting shoe 87 with a source of current 91. The source of current 91 is connected by suitable wiring with the signals 84 and 85, which in turn are connected by suitable wiring with the axle 70 of the engine. As the rail is connected with rail 86 by a bonding wire 92, the current will flow through the signals 84 and 85 when the shoe 87 is in the position shown in Fig. 6, but will not flow when shoe 87 75 is out of contact with rail 86. In this way the stop rails are arranged in certain relationship to the rail 1 and the signal rails are arranged at a different place and engaged by an independent shoe. 80

In constructing the device, various forms of the invention above described may be used, but it will be noted that the same can be operated with the usual block signaling system now in use, and need not necessarily interfere with the speed of any train if the engineer cares to control the action of his engine. If desired, the rails shown in Fig. 3 could be operated by the usual semaphores now in use or the signal rail shown in Fig. 9 could be actuated by the usual semaphores or block signaling systems now in use. Other slight changes and adaptations of the device could be made without departing from the spirit of the invention which presents means for positively giving a signal and then stopping the train unless prevented from action by the active interference of the engineer. This will guard against accidents by reason of the death of the engineer or carelessness or incapacity of the engineer, but will not in any way cause unnecessary delays or stoppages when the engineer is properly attending to his business. 95 100 105

While I have shown the device as applied to a steam locomotive the device is equally applicable to locomotives or engines driven by any other power as electricity, gas, oil, etc., and when the word steam or locomotives is used it is intended to cover power of any kind and a locomotive or engine of any kind. 110

Having thus described my invention I claim as new and desire to secure by Letters 115 Patent:—

1. In a train signal and stop, a power controlling valve, an air brake valve a signal rail arranged adjacent the rails of a track, a stop rail arranged in line with said signal rail and having a contact periphery on a different horizontal level, a shoe pivotally mounted on the locomotive adapted to be engaged by said rails successively and moved a predetermined distance thereby, 120 said signal rail moving the shoe a certain distance and said stop rail moving the shoe a different distance, a rod actuated by said shoe, signal mechanism set in motion by said rod when said shoe is moved by said 125 130

signal rail, and actuating mechanism, holding mechanism for said actuating mechanism, said holding mechanism being released by said rod when said shoe is actuated by said stop rail, said actuating mechanism being connected with said power controlling valve and said air brake valve so as to shut off power when released and apply the air brakes.

2. In a signal and train stopping device, a signal rail, a stop rail spaced from said signal rail having engaging surfaces on a different horizontal plane to said signal rail, a contact shoe pivotally mounted on an engine adapted to be moved pivotally different distances by said signal rail and said stop rail, a reciprocating member actuated by said shoe, a signal set in motion by said reciprocating member when said shoe is actuated by said signal rail, a throttle closing mechanism including a spring for actuating the same and a holding member for holding said throttle closing mechanism against action, said holding member being actuated when said shoe is actuated by said stop rail.

3. In a train signal and stopping device, the combination with a release valve for the air brake system of a train and a throttle valve on the engine, of a throttle lever connected with said throttle valve for actuating the same, a lever rigidly secured to the valve in the air brake system, a link pivotally mounted on said throttle valve lever formed with a slot in one end, a pin extending through said slot and rigidly connected with the lever secured to the air brake system valve whereby the throttle valve lever has a partially independent movement, a spring actuated means associated with said throttle valve lever for moving the same in one direction for closing the throttle valve and for opening the air brake valve, a pair of hook catches for holding said spring normally against movement, a reciprocating member for disconnecting said hook members, and means arranged along the track for actuating said reciprocating member.

4. In a train stopping device, the combination with a throttle valve and a valve for opening the air brake system, of a reciprocating member for actuating said valves, a sliding block for actuating said reciprocating member, a spring acting on said sliding block, a housing carrying said spring and said sliding block, a shaft formed with a hook end said shaft being connected with said block and when held against movement causing said spring to remain inactive, a pivotally mounted locking hook adapted to engage the hook end of said shaft, means acting on said shaft for causing the hook end thereof to engage said locking hook, a reciprocating member associated with said locking hook for causing the disengagement thereof when moved in one direction, and

means arranged along the track for operating said reciprocating member.

5. In a stopping device for trains, the combination with a throttle valve and an air brake system controlling valve arranged in an engine, of a throttle valve lever formed with a shoulder or lug near one end, means for connecting the throttle valve lever with the valve of the air brake system which will cause movement to be transmitted from the throttle valve lever to the valve of the air brake system for opening said last-mentioned valve when the throttle valve is closed, an operating bar pivotally connected with said throttle valve lever, a sliding block formed with an aperture for receiving the end of said operating bar, a hook pivotally mounted on said sliding block and adapted to move over the shoulder on said throttle valve lever when said block has been moved in one direction for holding the throttle valve closed, a spring for actuating said sliding block, a retaining bar formed with a hook for normally holding said spring from acting, a locking member for normally engaging said hook end, a movable member for unlocking said hook end in order to allow said spring to operate and means arranged along the track on which the engine is mounted for actuating said movable member.

6. In a train signal and stopping device, the combination with an air brake system valve, and a throttle valve, of means for actuating said valves for turning off the power and apply the brakes, said means comprising a spring-pressed member connected with the throttle valve lever, a shaft connected with said spring-pressed member having a hook end for normally preventing the action of said spring, a pivotally mounted locking hook for engaging the hook end of said shaft, and a resetting lever acting on said shaft for causing the hook end of said shaft to engage said locking hook, a reciprocating bar designed to move said locking hook to a disengaged position when moved in one direction, means arranged adjacent the tracks for actuating said reciprocating bar, a signaling member, and means connected with said reciprocating bar for setting in motion said signaling member when the reciprocating bar has been moved.

7. In a train signaling and stopping device, means arranged in the cab of a locomotive for turning off the power and applying the air brake, a reciprocating rod for controlling said means, a signal device arranged in the cab of said locomotive, a projecting member arranged on said reciprocating bar designed to be actuated upon the first movement of the reciprocating member for setting in motion said signal device previous to the actuation of the means for turning off the power and applying the air brakes,

- means arranged adjacent the track for moving said reciprocating bar so as to actuate said signal, and a separate member for moving said reciprocating bar a different distance from said last mentioned means, whereby the bar will operate the means for turning the power off and applying the brake.
8. In a train signaling and stopping device, means arranged in the cab of a locomotive for shutting off the power and applying the air brakes, a signal device arranged in said cab, a substantially vertically reciprocating rod for controlling the means for turning off the power and applying the air brakes, a sliding member having a lost motion connection with the upper end of said reciprocating rod said sliding member being formed with a projection, for causing the actuation of said signal device when the sliding member is actuated, a pivotally mounted arm connected with said sliding member, a rock shaft rigidly secured to said arm, a shoe connected with said rock shaft for operating the same, and a contact rail engaging said shoe for operating the shoe.
9. In a device of the character described, mechanism arranged upon a locomotive for first turning off the power and then applying the air brakes, a spring pressed reciprocating rod connected with said mechanism, said spring pressed rod causing said mechanism to operate when released, a catch for holding said spring pressed rod against movement, an operating rod provided with a co-acting catch for interlocking with the first mentioned catch and holding said first mentioned catch against movement, means alongside of the track on which the locomotive is positioned for moving said operating rod a predetermined distance, whereby said catches are disengaged, thus releasing said spring pressed rod.
10. In a train signaling and stopping device, a signaling device arranged in the cab of a locomotive, a reciprocating bar for operating said signaling device, a controlling valve for an air brake system means for controlling the power and said valve said means including a reciprocating hook member, a pivotally mounted hook adapted to engage the first mentioned hook member for holding the same against movement, and means loosely connecting said pivotally mounted hook with said reciprocating bar, means arranged along the track for moving said reciprocating bar a certain distance whereby said signaling device will be operated without disconnecting said pivotally mounted hook from said reciprocating hook member, and a stop rail arranged alongside the track for actuating said reciprocating bar for causing the same to disconnect said pivotally mounted hook from said reciprocating hook member, whereby said controlling means for the power and air brake system is permitted operation.
11. In a train signaling and stopping device, mechanism for first turning off the steam and then apply the air brakes, a catch for holding said mechanism normally against operation, a rod provided with a co-acting catch for interlocking with said first mentioned catch and holding said first mentioned catch against movement, means alongside of the track on which the locomotive is positioned for moving said rod a predetermined distance, a signal device operated by said rod when moved by said means, and an independent member arranged alongside of said track for moving said rod a sufficient distance for causing the same to disengage said catches, whereby the mechanism for turning off the steam and applying the air brakes will be released.
- In testimony whereof I have signed my name to this specification in the presence of two subscribing witnesses.
